UNITED STATES PATENT OFFICE

RUDOLF POPP, OF VALPARAISO, INDIANA, ASSIGNOR TO MCGILL MANUFACTURING COMPANY, A CORPORATION OF INDIANA

SWITCH MOVEMENT

Application filed June 3, 1929. Serial No. 368,006.

My invention relates to switches and more particularly to an improved switch movement mechanism.

The principal purpose of this invention is to provide a device of this character wherein simple and efficient means are provided for translating the rocking motion of a switch lever to rotary action of a projecting contact carrying device.

It is also a purpose of this invention to provide a device of this character in which the elements may be made in compact flat form so that the completed switch will take up a minimum amount of space.

Other and more detailed objects of the invention will appear as the description proceeds in connection with the accompanying drawing wherein one form which my invention may take is illustrated. It is to be understood, however, that I do not intend to limit myself to the exact details shown and described, but that I intend to avail myself of all such modifications as would occur to one skilled in this art and as fall within the scope of the claims.

In the drawing:

Fig. 1 is a top plan view of the switch with the cover removed and the top mounting piece also removed to expose the mechanism;

Fig. 2 is a section on the line 2—2 of Fig. 1 with certain portions being shown in full lines for the sake of clearness;

Fig. 3 is an end view taken from the left of Fig. 1;

Fig. 4 is a section on the line 4—4 of Fig. 3.

Referring now in detail to the drawing, the switches house in a housing such as indicated at 5 having a removable cap 6 and having a suitable lining 7 of insulating material. The frame of the switch consists of upper and lower sheets 8 and 9 of insulating material into which sheets the side terminal posts 10 and 11 are suitably riveted or otherwise secured and into which a U-shaped mounting member 12 is also fixed.

The side members 10 and 11 as shown carry a pair of contacts 13 and 14 which are in the form of plates having the upwardly extend-

ing inverted U-shaped spring portions 15 and 16 which as shown most clearly in Fig. 1 are provided on the free leg of the U-shaped portion with suitable contacts 17 and 18. From an inspection of Fig. 1 it will be noted that these contacts are so positioned as to be diametrically opposite each other with respect to the center of rotation of the bridging contact means 19. It will also be noted from an inspection of Fig. 1 that the members 13 and 14 are duplicates in all detail so that one may be readily interchanged for the other. The plates 10 and 11 carry the terminal screws 20 and 21 by means of which the switch may be inserted in a circuit.

The movable bridging contact member consists of a stub shaft 22 which has pressed thereon a lower insulating washer 23, a bridging contact element 24 which cooperates with the ratchet wheel 25 of insulating material, and in addition has pressed thereon an insulating washer 26, and a second smaller ratchet wheel 27 which may or may not be of insulating material as desired.

The shaft 22 may be rectangular in cross section to prevent rotation of the elements just described thereon, but the ends of the shaft are, as shown clearly by Fig. 2, round and pivoted in the members 8 and 9. The contour of contact member 24 is shown more clearly in Fig. 4, this member being made of a flat disc of material cut out as shown at 28 to provide a rectangular opening and has outwardly extending portions at 29, 30, 31, and 32 which portions are bent upwardly over the adjacent teeth of the ratchet member 25 so that alternate teeth of this ratchet member are surfaced with a contacting element. The face of the teeth of this ratchet member are of importance as will be brought out later, these teeth being made of a long rounded sloping portion 33 and a steep straight intermediate portion 34 which permits the spring contacts 17 and 18 to force the ratchet wheel in the direction shown by the arrow in Fig. 4 when these spring contacts pass from the portion 33 onto the portion 34 of the teeth thus giving a snapping action for the separating action of the contacts.

The means for moving the shaft 22 and

the elements thereon step by step in the proper direction consist of a U-shaped guide member 36 which is slotted as shown at 37 and 38 to receive the ends of the shaft 22 and 5 slide thereon, this U-shaped member being secured to a link 39 that is in turn connected by means of the pivotal connection 40 to the operating lever 41 which, as shown, has a rounded rim 42 working in a recess 43 of the 10 screw threaded mounting portion 44 of the switch. This screw threaded mounting portion is, as shown in Figs. 1 and 2, secured to the U-shaped member 12 so as to be rigid therewith.

15 The spring 45 encircles the link 39 and forces the U-shaped member 36 against the enlarged head 39' of the link 39. This spring also maintains an operating pawl 46 in proper position to engage the teeth of the 20 ratchet 27. This pawl has a turned over portion at 47 against which the spring bears and has an extended spring portion 48 that is hooked over as at 49 to hook into the teeth of the ratchet 27.

25 Now it will be seen that as the lever 41 is rocked in any direction on its universal mounting or pulled directly outward, it will pull the link 39 outwardly against the tension of the spring 45 to move pawl 46 and 30 U-shaped member 36 to the right from the position shown in Figs. 1 and 2. This causes the pawl 46 to engage ratchet 27 and move the shaft 22 in a clockwise direction, as shown in Fig. 1, a distance sufficient to bring the contacts 17 and 18 over the end of the surfaces 33 upon which they are resting. These contacts 17 and 18 then will, due to the resiliency of the U-shaped portions 15 and 16, slide down the faces 34 of the teeth on ratchet 25 35 and force the ratchet to turn a further distance in a clockwise direction.

40 When the lever 41 is released spring 45 will return to the position shown in Fig. 1 and set the pawl 46 so as to engage with the 45 next succeeding tooth on the ratchet 27, and in this manner the rocking action of the lever 41 is translated into a step by step rotating movement of the bridging contact member 24 so as to cause it to alternately connect and 50 disconnect stationary contacts 17 and 18. The free mounting of the shaft 22 also permits of a snap action of the switch both in making and breaking contact which gives a quick break that is very essential in devices 55 of this character.

From the above description it is thought that the simplicity and ruggedness together with the advantages thereof in other ways will be clear to those skilled in this art; and, 60 having thus described my invention, what I claim as new and desire to secure by Letters Patent is:

1. A switch comprising a frame including spaced supporting members, stationary contacts on said frame, a bridging contact unit

carried by said frame, said unit having a spindle journaled in said members, a lever rockably mounted on the exterior of said frame and connecting means for causing the unit to rotate step by step upon rocking said 70 lever comprising ratchet teeth on said unit, a substantially U-shaped guide member, link means connecting the base of said guide member to said lever, the legs of said guide member being guided by a portion of said unit and a pawl positioned by said guide member to engage said ratchet teeth.

2. A switch comprising a frame including spaced supporting members, stationary contacts on said frame, a bridging contact unit carried by said frame, said unit having a spindle journaled in said members, a lever rockably mounted on the exterior of said frame and connecting means for causing the unit to rotate step by step upon rocking said 80 lever comprising ratchet teeth on said unit, a substantially U-shaped guide member, link means connecting the base of said guide member to said lever, the legs of said guide member being guided by a portion of said unit and a pawl positioned by said guide member to engage said ratchet teeth.

3. A switch comprising a frame including spaced supporting members, stationary contacts on said frame, a bridging contact unit carried by said frame, said unit having a spindle journaled in said members, a lever rockably mounted on the exterior of said frame and connecting means for causing the unit to rotate step by step upon rocking said 85 lever comprising ratchet teeth on said unit, a substantially U-shaped guide member, link means connecting the base of said guide member to said lever, the legs of said guide member being guided by a portion of said unit and a pawl positioned by said guide member to engage said ratchet teeth.

90 4. A switch comprising a frame including spaced supporting members, stationary contacts on said frame, a bridging contact unit carried by said frame, said unit having a spindle journaled in said members, a lever rockably mounted on the exterior of said frame and connecting means for causing the unit to rotate step by step upon rocking said 95 lever comprising ratchet teeth on said unit, a substantially U-shaped guide member, link means connecting the base of said guide member to said lever, the legs of said guide member being guided by a portion of said unit and a pawl positioned by said guide member to engage said ratchet teeth.

100 5. A switch comprising a frame including spaced supporting members, stationary contacts on said frame, a bridging contact unit carried by said frame, said unit having a spindle journaled in said members, a lever rockably mounted on the exterior of said frame and connecting means for causing the unit to rotate step by step upon rocking said 105 lever comprising ratchet teeth on said unit, a substantially U-shaped guide member, link means connecting the base of said guide member to said lever, the legs of said guide member being guided by a portion of said unit and a pawl positioned by said guide member to engage said ratchet teeth, said unit comprising an insulating body having a metallic bridging contact on one side thereof and a ratchet wheel on the side opposite said bridging contact.

110 In witness whereof, I hereunto subscribe my name this 15th day of May, A. D. 1929.

RUDOLF POPP.
